CLAIM

The ornamental design for a ring light, as shown and described.

DESCRIPTION

FIG. 1 is a perspective view of a ring light showing my new design;

FIG. 2 is a rear elevational view of the ring light of FIG. 1; FIG. 3 is a front elevation view of the ring light of FIG. 1; FIG. 4 is a right side elevational view of the ring light of FIG. 1;

FIG. 5 is a left side elevational view of the ring light of FIG. 1;

FIG. 6 is a top plan view of the ring light of FIG. 1; and, FIG. 7 is a bottom plan view of the ring light of FIG. 1. The broken lines shown in the drawings depict portions of the ring light that form no part of the claimed design.

1 Claim, 5 Drawing Sheets
